UNITED STATES PATENT OFFICE.

LOUIS C. VANDERLIP, OF ELKHART, INDIANA.

EXPLOSION-ENGINE.

1,251,847.

Specification of Letters Patent.

Patented Jan. 1, 1918.

Application filed September 4, 1913. Serial No. 788,069.

To all whom it may concern:

Be it known that I, LOUIS C. VANDERLIP, a citizen of the United States, residing at Elkhart, in the county of Elkhart and State 5 of Indiana, have invented certain new and useful Improvements in Explosion-Engines, of which the following is a specification.

The invention relates to an improvement in explosive engines of the two-cycle type, 10 and more particularly to the control of the admission and exhaust of the motive fluid through the medium of a reciprocating element encircling the piston and operated by the main shaft.

15 The objects of my invention are as follows, first, the production of a two stroke cycle engine in which the fuel gases are initially inspired and compressed in the cylinder top by an improved form of sleeve valve, or control element, second, the use of intercommunicating compression chambers to produce efficiency in initially inspiring and compressing the fuel gas, third, the production of an engine of the class described in which the fuel gas losses by leakage in the initial compression chamber are reduced to the minimum by the adoption of an improved form of sleeve valve head, or pump, and fourth, the introduction of means 20 on the sleeve valve whereby the necessity for an additional valve of any character is eliminated and the motor height is reduced to the minimum. Other objects of my invention will appear from time to time and 25 be mentioned and described herein.

The invention in the preferred details of the construction will be described in the following specification, reference being had particularly to the accompanying drawings, 30 in which:—

Figure 1 is a sectional view of an engine constructed in accordance with my invention, the view being shown in distinct halves, respectively representing the opposing strokes of the piston.

Fig. 2 is an enlarged broken sectional view illustrating the base or lower portion of the engine, illustrating the operating means for the control element.

50 Fig. 3 is a section on line 3—3 of Fig. 5.

Fig. 4 is an enlarged broken sectional view, partly in elevation illustrating a control element in an extreme upper or gas admission position.

55 Fig. 5 is a similar view with the control

element in an extreme lower or cylinder charge admitting position.

Fig. 6 is a broken elevation of the control element.

Referring particularly to the accompanying drawings 1 represents the main casing, within which, as is usual, is provided a concentric annular wall 2, forming what will be hereinafter termed the main cylinder. The space intermediate the cylinder and 60 casing wall is formed by transverse partitions 3 to provide the usual water jacket 4 and the exhaust chamber 5, the cylinder communicating with the latter by a series of ports 6. The casing wall is of greater 65 length than the cylinder, and the upper end of said casing is closed by what may be termed the stationary piston 7, centrally formed to receive a spark plug 8 and having the usual water jacket space 9 interiorly 70 thereof. The stationary piston has the lateral head 10 closing the upper end of the casing and a depending central portion 11 forming the stationary piston proper which depends within the casing. The lower end 80 of the depending portion 11 terminates some distance above the upper end of the cylinder 2, and has an external diameter somewhat less than the internal diameter of the cylinder. 85

A motive fluid control member 12 is provided for operation within the cylinder, said member comprising a sleeve 13 slidably operating within the cylinder and formed at its upper end with an annular lateral extension 14 forming what I term a compression head. The head 14 operates in the space included between the depending portion 11 of the stationary piston and the casing wall, which space, as 15 will be hereinafter termed the compression chamber. The compression head 14 is formed with an annular recess 16 closed by the outer wall 17 of the head, which wall has slidable engagement with the casing wall, and is 100 packed at 18 to prevent leakage, the recess 16, which will be hereinafter termed the charging chamber, opening to the interior of the control element through a series of ports 19. The annular wall 20 forms a partial vertical division of the compression chamber, in the inner portion of which the compression head 14 operates, and in the outer portion of which the charge is localized under compression, and from whence 105 110

its entry into the cylinder is controlled by and conducted through said compression head, as will be hereinafter more fully described. The ports 21 are of greater height 5 longitudinally of the cylinder than the ports 19.

The compression chamber 15 is at an appropriate point of the casing divided by parallel partitions 22 to form an inlet chamber 10 23 open to the compression chamber, except for the control element as will later appear. The inlet chamber 23 is in communication, through a channel 24, with the carburetor (not shown), and the communication between 15 the inlet chamber and the compression chamber is through a comparatively reduced port 25.

The control element 12 is provided on its outer wall 17, and in line with the port 25, 20 with what may be termed a cut-off extension 26, the same being in the form of a depending portion of said wall adapted to fully and completely cover the port 25 in certain positions of said control element. The compression chamber between the depending portion 25 11 of the stationary piston 7 and the casing wall, within which the head 14 operates, is extended forward toward the cylinder 2 and beyond the top thereof and around the upper end thereof to accommodate the inward movement of the cut-off extension 26 and to 30 reduce the compression on the compression movement of the head 14.

The sleeve section 13 of the control element, which as previously stated operates within the cylinder 1 is formed at an appropriate point in its length with a series of horizontally aligned ports 27 designed to establish communication between the interior 40 of the sleeve 13 and the exhaust port 6 from the cylinder, the ports 27 being of less height longitudinally of the cylinder than the ports 6.

A piston 28 of any usual or preferred type 45 is mounted for reciprocation within the sleeve section 13 of the control element, the piston being packed at 29 in the usual manner, and packing 30 being also interposed between the sleeve section 13 of the control element and the stationary piston said packing being preferably arranged in an exterior wall of said stationary piston.

The piston 28 is operated in the usual manner from the main crank pin 31 of the 55 crank shaft 32, and said shaft carries an auxiliary and shorter crank 33 to which the sleeve extension 13 of the control member is connected and operated by a rod 34.

In operation assuming the piston 28 at its upper limit of movement, in which position 60 the control element 12 will be also at its upper limit of movement, it will be apparent that the cut-off extension 26 of the control element will be so elevated as to uncover the port 25 from the inlet chamber. The motive

fluid may now enter the compression chamber 15, below the compression head of the control member it being understood that the upward movement of said head tends to create a partial vacuum in said compression chamber to draw in a charge immediately upon the uncovering of the port 25. As the parts move downwardly, from the position illustrated in Fig. 4, it will be obvious that the port 25 is closed against the further admission of gas and the head operates to compress the gases in the compression chamber. The ports 21 opening from the compression chamber are of course closed during this movement by the solid wall of the sleeve extension of the control member, and this closed condition of the compression chamber is maintained during nearly the full stroke of the control member. The charge in the compression chamber is thus fully compressed until the ports 19 of compression head of the control member register with the ports 21 from the compression chamber, at which time the gas of the compression chamber, under full compression, enters the 80 charging chamber 16, and thence to the interior of the sleeve 12 which is in effect the true cylinder.

By reason of the relative movements of the piston and control element the exhaust 95 ports 27 register with the exhaust ports 6 of the cylinder slightly before the charging ports 19 and 21 are in registry, and hence the possibility of back pressure is eliminated and a rapid and effective exhaust secured. 100

As a result of the construction described it will be obvious that crank case compression is eliminated; that the gases are initially compressed beyond the cylinder and delivered under such compression by the most direct route to the cylinder, the inlet ports 23, 21 and 19 being substantially in the same direct line or plane; and that the compression head control of the inlet port 25 eliminates the necessity of a valve of usual type for 110 such control.

By extending the cut-off member 26 downward from the sleeve head 14 and extending the compression chamber 15 downward around the cylinder upper end, into which 115 chamber extension the cut-off member 26 may be projected on its downward movement with the sleeve head 14, the height of the engine as a whole is reduced to the minimum and the port 25 may be, and preferably is, located in substantially the same plane with ports 21, 21, and substantially diametrically opposite, or in the same plane with, the lower face, or bottom end, of the stationary piston 11.

Having thus described my invention, what I claim is:

1. An explosion engine comprising a cylinder, a casing provided with intercommunicating compression chambers, a con- 130

trol element operative as a compression piston in one of said chambers and provided with ports adapted to establish communication between said chambers and the cylinder at a predetermined point in its travel, a piston, and means for relatively operating said piston and control element.

2. An internal combustion engine comprising a cylinder; a casing beyond the cylinder forming a plurality of compression chambers the partition wall whereof is provided with ports; a reciprocatory member mounted in the cylinder and provided with a head which is fitted within one of said compression chambers and operative therein as a piston, said head having a chamber therein which is provided with ports adapted to register with said partition wall ports, said head chamber being provided also with ports adapted to place the head chamber and the explosion chamber in communication; a piston; and means for relatively operating said reciprocatory member and said piston.

25 3. An internal combustion engine comprising a cylinder; a casing beyond the cylinder forming a plurality of compression chambers the partition wall whereof is provided with ports; a reciprocatory member mounted in the cylinder and provided with a head which is fitted within one of said compression chambers and operative therein as a piston, said head having a chamber therein which is provided with ports adapted to register with said partition wall ports, said head chamber being provided also with ports adapted to place the head chamber and the explosion chamber in communication; an inlet port in communication with one of 40 said compression chambers; and means carried by the head of said reciprocatory member for governing said inlet port.

4. In an internal combustion engine, the combination of a cylinder; a casing provided with intercommunicating compression chambers; an inlet port for one of said chambers; a reciprocatory member having a head operative as a piston within the interior of said compression chambers; means carried by said reciprocating member head for governing said compression chamber inlet port; a piston; and means for relatively operating said piston and reciprocating member.

25 5. An explosion engine comprising a cylinder, a casing provided with intercommunicating compression chambers and an intake port in communication with one of said chambers, a control element operative as a compression piston in one of said chambers controlling said inlet port and provided with ports adapted to establish communication between said chambers and the cylinder, a piston, and means for relatively operating 35 said piston and control element.

6. An explosion engine comprising a cylinder, a casing provided with intercommunicating compression chambers and an intake port in communication with one of said chambers, a control element provided with a head operative as a compression piston in one of said chambers, and outlet ports formed in said head adapted to establish communication between said chambers and the cylinder, a piston, and means for relatively operating said piston and control element.

70 7. An explosion engine comprising a cylinder, a casing partitioned to provide intercommunicating inner and outer compression chambers, the partition being formed with outlet ports, an intake member having an inlet port formed in said partition to provide communication between said member and the inner compression chamber, a control element provided with a head to control said inlet port and operating as a piston in the inner compression chamber, ports formed in said head and adapted to register with the outlet ports to establish communication between the outer compression chamber and the cylinder, a piston, and means for relatively operating said piston and control element.

75 8. An explosion engine comprising a cylinder, a casing partitioned to provide intercommunicating inner and outer compression chambers, the partition being formed with outlet ports, an intake member having an inlet port formed in said partition to provide communication between said member and the inner compression chamber, a control element operatively mounted within said cylinder provided with a head to control said inlet port and operating as a piston in said inner chamber, ports formed in said head and adapted to register with said outlet ports to establish communication between the outer chamber and the cylinder, a piston operating within the control element, and means for simultaneously and relatively operating said piston and control element.

90 9. In an internal combustion engine, the combination of a cylinder; a casing provided with intercommunicating compression chambers, one of which has a ported wall; a reciprocating member having a head operative as a compression piston within the ported wall chamber, said head being provided with a charge receiving chamber which is alternately in and out of registration with the port in said compression chamber wall and the explosion chamber; a piston; and means for relatively operating 105 said piston and reciprocating member.

10. In an internal combustion engine, the combination of a cylinder and casing having bores of different diameters, the larger of said bores serving as a compression cham-

ber; a reciprocatory member within the smaller bore and carrying a head operative as a compression piston within said compression chamber, said reciprocating member head having a charge receiving chamber therein adapted to establish communication between said compression chamber and the engine explosion chamber at substantially the end of an inward movement thereof and to be out of communication with said compression chamber during the major portion of both outward and inward movements thereof; a piston; and means for relatively operating said piston and reciprocating member.

11. In an internal combustion engine, a cylinder; a casing provided with a compression chamber, said compression chamber being extended laterally, the wall of said compression chamber bore having a port which is in communication with said compression chamber lateral extension; a reciprocatory member which is provided with a chambered head, said head being fitted within said compression chamber and operative therein as a piston, said head chamber being adapted to register with said compression chamber wall port for establishing communication between said compression chamber and its extension and the explosion chamber; a piston; and means for relatively operating said piston and reciprocatory member.

12. In an internal combustion engine, a cylinder; a casing provided with a compression chamber, said compression chamber being extended laterally and downward around the upper end of the cylinder, the wall of said compression chamber bore having a port which is in communication with said compression chamber and its lateral extension; a reciprocatory member which is provided with a chambered head, said head being fitted within said compression chamber and operative therein as a piston, said head chamber being adapted to register with said compression chamber wall port for establishing communication between said compression chamber and its extension and the explosion chamber; a piston; and means for relatively operating said piston and reciprocatory member.

13. In an internal combustion engine, the combination of a cylinder; a casing provided with a plurality of intercommunicating compression chambers, one of said chambers being extended downward around and encompassing the outer periphery of the upper end of the cylinder; a reciprocatory member arranged within the cylinder and provided with a head operative as a piston and fitted within one of said compression chambers; a piston; and means for relatively operating said piston and reciprocatory member.

14. In an internal combustion engine, the

combination of a cylinder; a casing provided with a plurality of intercommunicating compression chambers; a reciprocatory member arranged within the cylinder and provided with a head operative as a piston and fitted within one of said compression chambers; a stationary piston projecting within one of said compression chambers and into said reciprocatory member, said stationary piston terminating at its lower end intermediate the upper end of the cylinder and the upper end of said casing; a piston; and means for relatively operating said piston and reciprocatory member.

15. In an internal combination engine, the combination of a cylinder and casing having bores of different diameters, the larger of said bores being a compression chamber, said compression chamber being extended downward around the upper end of said cylinder; an inlet port in communication with said compression chamber; a reciprocatory member provided with a head which is fitted within said compression chamber, said head carrying a cut-off member which alternately opens and closes said inlet port and is projected into said compression chamber extension on the downward movement thereof; a piston; and means for relatively operating said piston and reciprocatory member.

16. In an internal combustion engine, a cylinder; a casing provided with a compression chamber, said compression chamber having an extension, the wall of said compression chamber bore having a port which is in communication with said compression chamber and its extension; an inlet port in communication with said compression chamber; a reciprocatory member provided with a chambered head which is fitted within said compression chamber and operative therein as a piston, said head chamber being adapted to register with said compression chamber wall port for establishing communication between said compression chamber extension and the explosion chamber; a cut-off member carried by the head of said reciprocatory member which is adapted to alternately open and close said inlet port; a piston; and means for relatively operating said piston and reciprocatory member.

17. In an internal combustion engine, a cylinder; a casing provided with a compression chamber; a stationary piston projecting into said compression chamber and spaced from the walls thereof; an inlet port in communication with said compression chamber and substantially in the same plane with the lower face of said stationary piston; a reciprocatory member provided with a head which is fitted within said compression chamber, said head carrying a cut-off member which alternately opens and closes said inlet port; a piston; and means for

relatively operating said piston and reciprocatory member.

18. In an internal combustion engine, a cylinder; a casing provided with a compression chamber, said compression chamber being extended downward around the upper end of said cylinder; a stationary piston projecting into said compression chamber and spaced from the walls thereof; an inlet port in communication with said compression chamber and located substantially in the same plane with the lower face of said stationary piston; a reciprocatory member provided with a head which is fitted within said compression chamber, said head carrying a cut-off member which alternately opens and closes said inlet port and is projected into said compression chamber extension on the downward movement thereof; a piston separate from said reciprocatory member and separately actuated; and means for relatively operating said piston and reciprocatory member.

19. In an internal combustion engine, the combination of a cylinder; a casing provided with a plurality of intercommunicating compression chambers; a stationary piston projecting into the inner of said compression chambers and spaced from the walls thereof; an inlet port in communication with one of said compression chambers and located substantially in the same plane with the lower face of said stationary piston; a reciprocatory member provided with a head which is fitted within one of said compression chambers, said head carrying a cut-off member which alternately opens and closes said inlet port; a piston; and means for relatively operating said piston and reciprocatory member.

20. In an internal combustion engine, the combination of a cylinder; a casing provided with a plurality of intercommunicating compression chambers; a stationary piston projecting into the inner of said compression chambers and spaced from the walls thereof; an inlet port in communication with the inner of said compression chambers and located substantially in the same plane with the lower face of said stationary piston; a reciprocatory member provided with a head which is fitted within the inner of said compression chambers, said head carrying a cut-off member which alternately opens and closes said inlet port; a piston; and means for relatively operating said piston and reciprocatory member.

21. In an internal combustion engine, the combination of a cylinder and casing having bores of different diameters, the larger bore being a compression chamber, said compression chamber being extended downward around the upper end of said cylinder; an inlet port in communication with said compression chamber; a reciprocatory member provided with a head which is fitted within said compression chamber, said head carry-

ing a cut-off member which alternately opens and closes said inlet port and is projected into said compression chamber extension on the downward movement thereof; a piston separate from said reciprocatory member and separately actuated; and means for relatively operating said piston and reciprocatory member.

22. In an internal combustion engine, the combination of a cylinder; a casing provided with a plurality of intercommunicating compression chambers; an inlet port in communication with the inner of said compression chambers; a reciprocatory member provided with a head which is fitted within said inner compression chamber, said head carrying a cut-off member which alternately opens and closes said inlet port; a piston; and means for relatively operating said piston and reciprocatory member.

23. In an internal combustion engine, the combination of a cylinder and casing having bores of different diameters, the larger of said bores being a compression chamber; an inlet port in communication with said compression chamber at one side thereof; a reciprocatory member provided with a head which is fitted within said compression chamber, said head carrying a segmental cut-off member which alternately opens and closes said inlet port; a piston separate from said reciprocatory member and separately actuated; and means for relatively operating said piston and reciprocatory member.

24. In an internal combustion engine, the combination of a cylinder and casing having bores of different diameters, the larger of said bores being a compression chamber; an inlet port in communication with said compression chamber; a reciprocatory member provided with a head which is fitted within said compression chamber, said head carrying an unported cut-off member which alternately opens and closes said inlet port; a piston separate from said reciprocatory member and separately actuated; and means for relatively operating said piston and reciprocatory member.

25. In an internal combustion engine, the combination of a cylinder and casing having bores of different diameters, the larger of said bores being a compression chamber; an inlet port in communication with said compression chamber; a reciprocatory member provided with a head which is fitted within said compression chamber, said head carrying a cut-off member extending downwardly therefrom and which alternately opens and closes said inlet port; a piston separate from said reciprocatory member and separately actuated; and means for relatively operating said piston and reciprocatory member.

26. In an internal combustion engine, the combination of a cylinder and casing having bores of different diameters, the larger of

said bores being a compression chamber; an inlet port in communication with said compression chamber at one side thereof; a reciprocatory member provided with a head 5 which is fitted within said compression chamber, said head carrying a cut-off member which alternately opens and closes said inlet port; a piston separate from said reciprocatory member; and means for relatively operating said piston and reciprocatory member.

27. In an internal combustion engine, the combination of, a cylinder and casing having bores of different diameters, the larger 15 of said bores serving as a compression chamber; a reciprocatory member carrying a head operative as a compression piston within said compression chamber, said head being provided with a fluid receiving chamber 20 which is out of communication with said compression chamber during a portion of

either stroke thereof; a piston; and means for relatively operating said piston and reciprocatory member.

28. In an internal combustion engine, a 25 cylinder; a casing provided with a compression chamber; a port in the wall of said compression chamber; a chamber beyond said compression chamber wall port and in communication with said port and said 30 compression chamber; and a reciprocatory chambered member arranged within said compression chamber, said chamber being adapted to register with said compression chamber wall port at a predetermined point 35 in the travel of said reciprocatory member.

In testimony whereof I affix my signature in presence of two witnesses.

LOUIS C. VANDERLIP.
